UNITED STATES PATENT OFFICE.

FREDERICK A. MERRIMAN, OF LOS ANGELES, CALIFORNIA.

STUB FOR BINDING LOOSE LEAVES.

1,170,175.

Specification of Letters Patent.

Patented Feb. 1, 1916.

Application filed January 8, 1915. Serial No. 1,152.

To all whom it may concern:

Be it known that I, FREDERICK A. MERRIMAN, a citizen of the United States of America, and a resident of Los Angeles, Los Angeles county, California, have invented certain new and useful Improvements in Stubs for Binding Loose Leaves, of which the following is a specification.

My invention relates to improvements in stubs for binding loose leaves, and the object of my improvement is to improve the method of binding together detachably the leaves used in loose leaf ledgers and the like, by securing the leaves to stubs in such a way as to permit the leaves to become separated flatly when spread apart, to facilitate their use in handling and to utilize practically the entire surfaces of the leaves for entries. This object I have accomplished by the means which are hereinafter described and claimed, and which are illustrated in the accompanying drawings, in which:

Figure 1 is a plan, on a reduced scale, and with parts broken away, of a stub having my improved securing means for loose leaves. Fig. 2 is a like plan of the device, showing parts of the stub and said securing means removed. Fig. 3 is an end elevation, full size, of my improved device. Fig. 4 is a transverse section of said device taken, full size, on the line *a*—*b* of said Fig. 1. Fig. 5 is an end elevation of an assemblage of said devices as grouped together in book form, with parts of both the stubs and leaves to be opened flatly apart.

Similar numerals of reference denote corresponding parts throughout the several views.

It is well known that loose leaves as ordinarily bound together in so called loose leaf ledgers and the like, have their inner marginal portions so compressed upon each other, and so much of said margins usurped by reason of the necessity of binding them together by stringing them on binding pins of the cover, that a large proportion of each leaf is impossible of utilization, while the book, as a whole, opens stiffly and partially, rendering it difficult to make insertions or entries. My device is intended to obviate these faults in construction and use. With these purposes in view, I arrange a plurality of loose leaves in a pile and form and adapt

like edges thereof to be detachably secured in a binding stub, so that a number of these 55 stubs may be bound or otherwise secured together. To insure flexibility in such an assemblage of stubs and consequent easy separation of one from another and especially to permit adjacent leaves to lie flatly 60 when spread apart, I form my improved binding stub of two rigid parts 1 and 2, being a pair of strips of book-board of like form and dimensions, and flexibly connected by means of a flexible envelop which forms 65 also the intermediate flexible connection 4. As shown, this envelop, as also its intermediate flexible part 4 between the strips 1 and 2 is formed of one piece of binding cloth or other suitable material flexed upon 70 itself to cover the strips and provide the hinge between them. The flexible hinge part 4 is made wide enough to insure ease in swinging the strip 2 with the attached leaves 10 in opening and using the assembled stubs when bound in book form. 75

The strip 2 is supplied with a plurality of rectangular openings 8 along one edge, and with relatively shallow grooves 16 on the opposite longitudinal edge directly opposite 80 from each other.

The numeral 5 denotes a binding clip made of a strip of spring steel doubled into U-shape and seated in the groove 16 to have its members embrace the narrowed part of 85 the body 2 and extend over the opening 8. Both the strip 2 and both members of said clip have like registering orifices 15 to receive a fastening annulus 6, whose ends may be spread to firmly secure the clip to the 90 strip 2. Both members of said clip have like rectangular orifices, out of line with each other, as shown at 7 and 14, for a purpose to be described hereinafter. Both the strip 2 and its cover 12 have their alined cut away 95 parts 8 and 13 made wider in height than the clip 5 to permit of ready assembling of the parts.

Each leaf 10 has its left-hand vertical edge cut away to provide spaced short tabs 100 9 which are of a height requisite to be received into the openings 9 of the strip 2, as best shown in said Fig. 2. It will be seen that these tabs are very short and therefore but little of the margin of the leaf is taken 105 up in the stub, thus leaving all the balance

of the leaf free for written entries. The left-hand ends of said tabs are separated from the opposite wall of the opening 8 by an interspace. This interspace permits a hook or the end of a short lever to be inserted thereinto through either of the openings 7 or 14 in the clip members, whereby the member acted upon may be spread apart sufficiently to allow a leaf to be inserted or removed from the stub.

10 When the leaves 10 are assembled in a pile with their tabs 9 in registration, the clip members may be engaged to clamp them tightly, which sufficiently prevents their being detached under the ordinary stresses of use.

15 The wings 11 being flexibly connected to the rigid strips 2, open out flatly, as shown in Fig. 5, together with any overlying leaves 10 to bridge across the interspace of the stubs when the latter are spread apart. It will be seen that thus the whole surface of each leaf may be used, since the flexible hinges 4 allow the stubs to freely separate 20 sufficiently for this result.

25 The clips 5 are reversible, and as many may be used on each strip 2 as necessary according to the height of the leaves 10. The stubs may be assembled and bound together 30 in any convenient manner, and with little binding expense, since the leaves 10 are already secured thereto. Any other securing means than that shown may be employed to secure the clip-members to the strip 2 without departing from the principle of this invention.

35 Having described my invention, what I claim as new, and desire to secure by Letters Patent, is:

40 1. Fastening means for loose leaves, consisting of a pair of elastic clamping arms adapted to detachably hold margins of a pile of leaves between them, and both arms having orifices out of line with each other 45 for the reception of a lever end.

45 2. Fastening means for loose leaves, consisting of a strip of relatively stiff elastic material doubled upon itself to provide spaced parallel plates, one of the plates having an orifice spaced from its free extremity, and means for securing said members upon an inclosed supporting body, with the extremities of the members including said orifice extending beyond the supporting body.

50 3. Fastening means for loose leaves, consisting of a supporting rigid strip, a plate of elastic material bent over said strip to provide a pair of opposed clips extending therebeyond and adapted to yieldingly clasp 55 a number of loose sheets between them, and means for securing both clips to said strip.

55 4. Fastening means for loose leaves, comprising a strip of relatively rigid material, a pair of elastic members secured to opposite sides of the strip to project therebeyond,

and a rivet securing said members to said strip.

5. Fastening means for loose leaves, comprising a strip of relatively rigid material having a recessed edge, a plate of elastic material doubled to provide a pair of spaced opposed clips embracing said strip, covering the recess therein and adapted to grasp yieldingly marginal tabs of a pile of loose sheets between them, and means for securing 75 said clips to said strip.

6. Fastening means for loose leaves, comprising a strip of relatively rigid material having a recess in one longitudinal edge, a plate bent to provide clip-members 80 embracing said strip to cover said recess, and a rivet securing said clips to the inclosed part of said strip, said plate having an opening to receive a lifting lever.

7. Fastening means for loose leaves, comprising a rigid strip, another rigid strip hinged thereto in spaced parallel relation, the second strip having a recess in its outer longitudinal edge, a plate bent to form spaced clip-members embracing the second 90 strip to cover the recess therein, and said members adapted to releasably grasp superposed tabs of a pile of loose leaves seated in said recess.

8. Fastening means for loose leaves, comprising a rigid strip, another rigid strip placed in spaced parallel relation therewith, a flexible connection between the adjacent longitudinal edges of said strips, the second strip having a recess in its outer longitudinal 100 edge adapted to receive marginal tabs from a pile of loose leaves, a pair of clip members secured on opposite sides of said second strip to overlie said recess and releasably grasp said tabs between them, the 105 recess being wider than the tabs extending thereinto to provide a cavity between the clips, and one clip having an orifice therethrough over said cavity.

9. Fastening means for loose leaves comprising two like rigid strips spaced apart, an envelop for said strips forming a flexible joint therebetween, one strip and its envelop both being marginally recessed, with the recess in said strip extending approximately 110 one-half the width of the strip, an elastic plate bent double to embrace the recessed part of the strip to have its extremities overlie the recess, means for securing the clip-members to the inclosed part of the strip, 115 one of said members having an opening into the said recess, and wing flaps extending from opposite sides of the outer longitudinal edge of said recessed strip.

10. Fastening means for loose leaves, comprising flexibly connected rigid strips, means for detachably securing superposed like marginal parts of a pile of loose leaves to one of said strips, and flaps extending from opposite faces of the last mentioned strip 125 130

to cover portions of the upper and lower surfaces of said pile of leaves.

11. Fastening means for loose leaves, comprising a rigid strip, flaps flexibly hinged to opposite faces thereof to project from one longitudinal edge thereof in spaced relation relative to each other, and means for releasably hinging marginal parts of a pile

of loose leaves to said strip between said flaps to swing freely together with the flaps. 10

Signed at Los Angeles, Cal., this 22nd day of Dec. 1914.

FREDERICK A. MERRIMAN.
